LIFT TRUCK

George V. Johnson, Portland, Oreg., assignor to
 Willamette Hyster Company, Portland, Oreg.,
 a corporation of Oregon

Application December 31, 1943, Serial No. 516,405

22 Claims. (Cl. 280—92)

The present invention relates to lift trucks and is particularly concerned with lift trucks of the type driven with an internal combustion engine and having at the forward end a pivotally mounted frame acting as a guide and a support for a carriage having a pair of forwardly extending lifting arms.

One of the objects of the invention is the provision of an improved lift truck of the class described, the structure of which is more compact, 10 sturdy, and makes more efficient use of available space to permit the use of larger pneumatic tires and still retain general over-all dimensions consistent with trucks of equal capacity using smaller diameter solid tires.

Another object of the invention is the provision of an improved steering mechanism for a lift truck of the class described which is simple yet effective and which is mounted on a conveniently movable support for the driver's seat so that the steering post and seat may be moved to a different position to permit access to the motor and/or other mechanism.

Another object of the invention is the provision of an improved lifting structure for trucks of the class described which permits a greater visibility for the operator, forwardly of the truck, through the elevator and its mechanism.

Other objects and advantages will be apparent from the following description and the accompanying drawings, in which similar characters of reference indicate similar parts throughout the several views.

Referring to the drawings, of which there are two sheets,

Fig. 1 is a side elevational view in partial section to show the muffler, showing the structure of a truck embodying the invention;

Fig. 2 is a horizontal sectional view taken on the plane of the line 2—2 of Fig. 1 looking in the direction of the arrows, showing the steering mechanism;

Fig. 3 is a fragmentary sectional view taken on the plane of line 3—3 of Fig. 2, looking in the direction of the arrows, showing the details of the mode of support of the seat on the housing;

Fig. 4 is a fragmentary sectional view on the plane of the line 4—4 of Fig. 2 looking in the direction of the arrows, showing the details of the construction of the bearing and steering shaft, by means of which the rear wheel is turned for steering;

Fig. 5 is a fragmentary sectional view taken on the plane of the line 5—5 of Fig. 2 looking in the direction of the arrows, showing the de-

tails of construction of one of the chain tightening sprockets;

Fig. 6 is a top plan view of the lift truck;

Fig. 7 is a vertical sectional view taken on the plane of the line 7—7 of Fig. 6 looking in the direction of the arrows.

The present vehicle preferably has its chassis in the form of an assembly of cast steel members which are also employed for housing and enclosing the mechanism and for providing the housings for a pair of laterally located mufflers.

Referring to Figs. 1, 6 and 7, the lift truck is there indicated in its entirety by the numeral 20 and its chassis frame by the numeral 21. 15 This chassis frame may comprise a pair of side panels 22 joined at the top under the feet of the operator by a transversely extending frame member 23 which also serves as a floor board, and joined at the rear by a vertically extending 20 partially cylindrical end wall 24.

At the forward end of the vehicle each of the side panels 22 is provided with a transversely extending wall 25, which is curved cylindrically and slightly spaced from each of the front wheels 26 to form a fender, and the wall 25 is joined to a forwardly extending supporting flange 27, which is secured to the front axle housing 28. In order to clear the wheels 26 and brake drums and brake housing 29, the forwardly extending 25 wall 27 slopes inwardly from 30 to 31, but has its 30 end portions 32 parallel to the side panels 22.

The forward end portions 32 are formed with the half cylindrical attaching flanges 33, which are adapted to fit the outside of the axle housing 28, and which are provided with a pair of apertures for receiving the two legs of a U-shaped bolt 34 that embraces the axle housing and passes through the flanges 33 to secure the chassis fixedly to the axle housing 28. At the rear end 40 of the chassis frame the side panels 22 also enclose a muffler chamber 35, which is formed by a top wall 36, bottom wall 37, side panel 22, inner wall 38, and two end walls 39, 40 (Fig. 1).

This muffler has its top wall 36 provided with a threaded bore at 41 for receiving the tail pipe 42, which has a vertical portion threaded into the bore 41 and a horizontal rearwardly extending portion discharging at 43 rearwardly of the chassis frame.

45 50 The exhaust is brought to the muffler chamber 35 by an exhaust pipe 44 on each side of the vehicle. The exhaust pipes pass in at an aperture 45 by means of a downwardly extending diagonal portion 46 and the pipes have a downwardly turned portion 47 in the chamber 35.

The top wall 36 of each muffler chamber 35 may also have a threaded filling opening which is closed by threaded plug 48 so that each muffler chamber may be filled with ordinary water to a level 49, which is slightly below the end 47 of pipe 44. The present muffler may under certain conditions be used without water. 50 indicates diagrammatically in Fig. 1 the power unit comprising an internal combustion engine which may be of the V-type so that its cylinders are arranged in two series, one series having its exhaust connected to each of the mufflers on each side of the vehicle.

The operation of these mufflers is as follows: The exhaust gases, sparks, carbon, etc., are discharged from the end 47 to the pipe 44 at high velocity directly toward the free surface of the water 49 and any burning particles are driven into the water and extinguished. As the exhaust gases at high velocity pass out of the pipe end 47 into exhaust chamber 35 they are permitted to expand freely into the larger space provided and the velocity energy is dissipated in this chamber. Successive waves of pressure are created in the chamber which are discharged through the tail pipe 42 to atmosphere and noise of the explosion of the engine is substantially muffled by use of this structure.

Due to the use of water there is assurance that sparks will not pass out of the tail pipes; and the construction is so arranged that the water is not blown from the muffler, thus permitting their use for relatively long periods without refilling.

The side panels 22 are also preferably joined at the rear top by the upwardly extending diagonal walls 51, 52 and at the rear by the frustoconical end wall 53. These tapered walls 51, 52, 53 may be integrally joined to a top wall 54 which carries an integral depending bearing housing 55 of substantially cylindrical shape. The bearing housing 55 is joined to the tapered walls 51-53, by reinforcing ribs 56-58, and this bearing housing is preferably formed with a plane annular lower end surface 59.

The bearing housing 55 has an inner cylindrical bore 60 and is provided at its upper and lower ends with the bearings 61, 62. These bearings may be similar in construction; each one consisting of a cylindrical bearing portion 63 and a radially extending thrust flange 64. The cylindrical portion 63 of each bearing has a pressed fit in the cylinder bore 60 and the radial flange 64 engages the end of this bearing housing 55 and determines the final position of the bearing.

Bearings 61, 62 are adapted to support for rotation, the vertically extending steering shaft 65 which has a cylindrical outer surface 66 engaging the cylindrical bores in the bearings 61, 62. This vertical steering shaft may form an integral part of a steering wheel supporting member 67, Fig. 7, which provides a support for the wheel 68 and its shaft 69, and also provides an integral counter-weight for counter-balancing the loads that may be carried by the front end of the vehicle beyond the axle for the front wheels 26.

This wheel supporting member 67 may have a lower plane surface 70 and a cylindrical side surface 71. Its upper surface 72 may also be plane but it is provided with an annular thrust surface 73 which is accurately machined, and which surrounds the vertical shaft 65 for engaging the lower thrust flange 64 of bearing 62.

The wheel supporting member 67 may be

formed of a cast metal member of considerable weight which has centrally located recesses 74 of sufficient size to receive the wheel 68 and axle 69. The recess 74 has the parallel side walls 75, 76 and the inner end wall 77, Fig. 1, but these recesses preferably open at the rear as well as at the bottom. Of course the recess is open at the bottom so that the wheel may project into engagement with the ground; and it is preferably open at the rear so that the wheel may be conveniently removed.

The wheel and its axle are preferably constructed substantially like the construction disclosed in my prior application, case 1, Serial 459,905, filed September 28, 1942, on Industrial trucks, which has issued as Patent No. 2,337,109 on December 21, 1943, and therefore need not be described in detail.

It is sufficient to say that the side walls 75, 76 are provided with sockets for receiving threaded members which engage the tapered ends of shaft 69 and which may be retracted sufficiently to permit the shaft 69 to be moved laterally out of these threaded members and out of the recess 74 with its wheel.

The vertically extending shaft 65 is also preferably made solid in order to utilize this space for a counter-weight, and at its upper end it is provided with a plane surface 78, Fig. 4, for engaging the sprocket plate 79 which is secured to this shaft by means of a plurality of screw bolts 80 passing through the sprocket plate and threaded into threaded bores in the top surface 78.

The sprocket plate 79 need not be provided with teeth, but it preferably has its upper and lower surfaces beveled at its peripheral edge as indicated 81, 82, so that the edge 83 is relatively narrow and is adapted to be received between the flanges 84 of the links of a sprocket chain 85. This chain may be endless and may be fixedly secured to the sprocket plate 79 by means of a screw bolt 86 at the right hand side of the sprocket plate as indicated in Fig. 4.

The top wall 54 at the rear end of the chassis frame which is supported by the side walls 51-53 and which carries the bearing housing 55 is also preferably formed with a cylindrical supporting surface 87 which is concentric with the vertical shaft 65, and with a horizontal annular surface 88, Fig. 3, Fig. 4, for rotatably supporting the seat and steering wheel structure.

The driver's seat 89 and the steering wheel 90 are carried by a rotatably mounted hollow arm 91, which has at its right end in Fig. 1, a circular housing 92 for enclosing the sprocket chain 85 and sprocket plate 79 and for supporting the arm 91 for rotation upon the cylindrical surface 87. The circular housing 92 is an integral part of arm 91 and has a partially cylindrical wall 93 which is provided at its lower edge with an annular thrust surface 94 and with an inwardly extending frame 95 having a cylindrical bearing surface 96, Fig. 3.

The surfaces 94 and 96 engage the surfaces 88 and 87 on the housing top 54 and the arm 91 is thus adapted to be rotated on the chassis frame. The circular housing 92 may be retained in place by a plurality of screw bolts 97 which have washers 98 with over-hanging flange 95 to serve as upper guides, permitting a sliding movement between flange 95 and washer 98 when the arm 91 is rotated. Screws 97 are threaded into bores 99 of the housing top 54.

The cylindrical housing portion 93 commun-

cates with the hollow arm 91 which has two parallel side walls 100, 101 spaced from each other sufficiently to house the sprocket chain 85. Arm 91 also has a top wall 102 through which bolts and spacers may be passed for securing the seat 89 to the arm 91.

The lower side of the arm 91 is also preferably closed by a bottom wall 103. The arm 91 is also provided adjacent the sprocket plate 79 with stub shafts 105 for rotatably supporting the idler pinions 104 which draw the sprocket chain in about the sprocket plate 79 so that the arm 91 may be narrow.

In order that the arm 91 and its circular housing 93 may be removed, the flange 95 is preferably provided with a plurality of circular slots 106 rotated a predetermined number of degrees away from the bolts 97, such as, for example, 30 degrees, and the slots 106 are large enough to pass the washers 98. Thus, if the arm 91 is rotated 30 degrees until all the slots register with the washer 98, the circular housing 93 may be lifted from its bearings and after detaching the chain 85 from the sprocket plate 79, the arm 91 with its assembled parts may be removed.

The top of the chassis frame which is formed by the two upwardly extending walls 22 may be open so as to permit access to the motor 50, but it is closed by means of a hood 107. Before this hood 107 can be removed, however, it is necessary to pivot the arm 91 in a counter-clockwise direction away from the levers 108, 109, Fig. 1, so that the hood can be removed by lifting it upward. Any suitable type of securing devices may be used for securing the hood 107, or it may be made of a relatively heavy cast metal member which is held in place due to its weight.

At its forward end, that is, the left hand end, Fig. 1 and Fig. 2, the hollow arm 91 is provided with an enlargement 110 having a curved end wall 111, and this enlargement is formed with an upper plane surface 112 having a circular bore 113 for receiving the steering column 114 and its housing 115. Steering column 115 preferably has a reduced cylindrical end portion which fits in a bore 112 where it may be secured by means of bolts, and the steering column housing is provided with a centrally located bore 116 serving as a bearing for the steering column 114.

At its lower end the steering column 114 carries a pinion 117 for engaging with a gear 118 that is fixedly secured to a stub shaft 119. Stub shaft 119 also carries a sprocket pinion 120 and is rotatably mounted in bearings in the top and bottom wall of the arm. Pinion 120 is provided with teeth of the type used on a sprocket wheel and is adapted to be engaged by the sprocket chain 85.

The operation of the steering mechanism is as follows:

The steering wheel 90 is fixedly secured to the steering column or shaft 114, and when it is turned it turns the pinion 117. The pinion 117 meshes with gear 118 which rotates shaft 119 and sprocket pinion 120.

Sprocket pinion 120 drives the chain 85 which is held engaging the sides of the sprocket plate 79 by the idlers 104. Whenever the chain 85 is driven it rotates the sprocket plate 79 and with it the vertical shaft 65 that forms a part of the wheel support for the rear wheel. Thus, the rear wheel may be turned as desired by means of the steering wheel 90 and the intermediate steering elements serve as a reducing gear, so that it requires a greater movement of the steering wheel

to turn the vehicle wheel, but less power is required at the steering wheel 90.

The idler sprockets 104 have their shafts 105 of the type shown in Fig. 5. Shaft 105 has an eccentrically disposed enlargement 121, and the enlargement 121 is cylindrical so that it may be received in a complementary bore 122 in the bottom wall 103 of the arm 91. Shaft 105 also has a reduced threaded extension 126 passing through a plate 124 which is secured in place by a screw bolt 125, and the nut 123 is adapted to clamp the eccentric portion 121 in any of a multiplicity of positions. For this purpose the plate 124 must be provided with an elongated slot for the threaded extension 126, but by means of this structure shaft 105 of each sprocket 104 may be moved inward or outward to tighten the sprocket chain.

In order that the seat supporting arm 91 may be held in its forwardly extending position the flange 95 may be made thicker at the rear or right side, Fig. 4, and provided with a tapered bore 127 for receiving the tapered end of a plunger 128. Plunger 128 slides in a bore 129 and is urged outwardly by the compression spring 130. When it is desired to turn the seat supporting arm, a screw driver or other tool may be inserted in the bore 127 to drive back the plunger 128 to effect its release.

When the said supporting arm is moved back to its forwardly extending position, as shown in Fig. 1, the plunger 128 automatically moves into bore 127 to lock the parts in that position.

The present steering equipment may be used on various types of vehicles, but it is peculiarly adapted to be used upon a vehicle of the type shown, comprising a lift truck, the forward end of which is provided with a vertically extending load-carrying frame 135 having an upper telescoping section adapted to be lifted by a hydraulic cylinder and piston and also having a carriage 220 slidably mounted on the vertical frame and provided with load-carrying arms 246, the carriage being lifted by means of the chain 147 fixed at one end and passing over a pulley on the hydraulic piston.

The vertical frame 135 is pivotally mounted upon stub shaft 150 by means of rearwardly extending arms 149 which are pivotally connected at 154 to a piston 155 mounted in cylinder 156, by means of which the vertical frame may be tilted.

It will thus be observed that I have invented an improved construction for lift trucks which is simple, sturdy and capable of being manufactured at a low cost and adapted to handle relatively heavy loads for its size and to transport them at a greater speed than the devices of the prior art. The present elevator construction is very stable and flexible in its handling and provides a maximum degree of visibility for the operator since only a single chain is used which is disposed in alignment with the piston and cylinder.

The steering arrangement is also very simple and effective and it is mounted on a removable arm with a seat for the operator so that the entire assembly of steering gear and seat may be moved to one side for access to the motor, or may be entirely removed.

While I have illustrated a preferred embodiment of my invention, many modifications may be made without departing from the spirit of the invention, and I do not wish to be limited to the precise details of construction set forth, but de-

sire to avail myself of all changes within the scope of the appended claims.

Having thus described my invention, what I claim is new and desire to secure by Letters Patent of the United States is:

1. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member.

2. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said tension driving member comprising a chain, and said driving member comprising a sprocket wheel.

3. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said tension driving member comprising a chain, and said driving member comprising a sprocket wheel, and said steering member comprising a wheel and shaft having a pinion at its lower end engaging gear means for driving said sprocket wheel.

4. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said chassis wall also being formed at its upper portion with a cylindrical bearing surface and an annular thrust surface, and a housing for

enclosing said plate and tension driving member and said second-mentioned driving member rotatably mounted on said latter cylindrical surface and thrust surface.

5. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate, and passing around a rotatable driving member located forwardly on said chassis, and a steering member for controlling said driving member, said chassis wall also being formed at its upper portion with a cylindrical bearing surface and an annular thrust surface, and a housing for enclosing said plate and tension driving member and said second-mentioned driving member rotatably mounted on said latter cylindrical surface and thrust surface, said housing also supporting a pair of rotatable idler members for drawing the driving tension member about said plate to reduce the necessary width of said housing.

6. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said chassis wall also being formed at its upper portion with a cylindrical bearing surface and an annular thrust surface, and a housing for enclosing said plate and tension driving member and said second-mentioned driving member rotatably mounted on said latter cylindrical surface and thrust surface, and guide means carried by said chassis engaging above an annular shoulder on said housing for retaining the housing on the chassis.

7. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said chassis wall also being formed at its upper portion with a cylindrical bearing surface and an annular thrust surface, and a housing for enclosing said plate and tension driving member and said second-mentioned driving member rotatably mounted on said latter cylindrical surface and thrust surface, and guide means carried by said chassis engaging

above an annular shoulder on said housing for retaining the housing on the chassis, said guide means comprising a plurality of washers and threaded bolts driven into the upper chassis wall, and said latter annular surface being formed with grooves for passing said washers when the housing is in a predetermined rotative position.

8. In an industrial truck, the combination of a chassis frame comprising a metal member formed at its rear end with a wall, said wall carrying at its upper portion a relatively large bearing housing having a vertically extending cylindrical bore with a rear wheel support comprising a metal member having a vertically extending shaft adapted to be received in said bore and supported therein for rotation about a vertical axis, a guide plate carried by the upper end of said shaft, a tension driving member secured to said plate and passing around a rotatable driving member located forwardly on said chassis, and a steering member for controlling said driving member, said chassis wall also being formed at its upper portion with a cylindrical bearing surface and an annular thrust surface, and a housing for enclosing said plate and tension driving member and said second-mentioned driving member rotatably mounted on said latter cylindrical surface and thrust surface, and guide means carried by said chassis engaging above an annular shoulder on said housing for retaining the housing on the chassis, said housing having a tapered socket, and said chassis carrying a tapered spring-pressed plunger for locking the housing against rotation on the chassis.

9. In a movable seat support for industrial trucks, the combination of a rear wheel housing having at its upper end an upwardly projecting cylindrical surface and having an annular thrust surface adjacent to said cylindrical surface, with a cover member having a cylindrical bore for receiving said cylindrical surface and having an annular thrust surface for engaging said annular surface, said cover having an inwardly extending flange surrounding said cylindrical bore, guide means carried by said rear wheel housing for supporting said cover for rotative movement about a vertical axis, said cover being provided with a radially projecting arm, and a seat carried by said arm and adapted to be moved to an operative position or to be rotated with said cover toward the side for permitting access to other parts of the industrial truck.

10. In a movable seat support for industrial trucks, the combination of a rear wheel housing having at its upper end an upwardly projecting cylindrical surface and having an annular thrust surface adjacent to said cylindrical surface, with a cover member having a cylindrical bore for receiving said cylindrical surface and having an annular thrust surface for engaging said annular surface, said cover having an inwardly extending flange surrounding said cylindrical bore, guide means carried by said rear wheel housing for supporting said cover for rotative movement about a vertical axis, said cover being provided with a radially projecting arm, and a seat carried by said arm and adapted to be moved to an operative position or to be rotated with said cover toward the side for permitting access to other parts of the industrial truck, said rear wheel housing being provided with a spring-pressed plunger, and said cover being provided with a bore for receiving said plunger whereby the cover may be locked against rotation with

the arm projecting forwardly to the operative position.

11. In a movable seat support for industrial trucks, the combination of a rear wheel housing having at its upper end an upwardly projecting cylindrical surface and having an annular thrust surface adjacent to said cylindrical surface, with a cover member having a cylindrical bore for receiving said cylindrical surface and having an annular thrust surface for engaging said annular surface, said cover having an inwardly extending flange surrounding said cylindrical bore, guide means carried by said rear wheel housing for supporting said cover for rotative movement about a vertical axis, said cover being provided with a radially projecting arm, and a seat carried by said arm and adapted to be moved to an operative position or to be rotated with said cover toward the side for permitting access to other parts of the industrial truck, said arm having an enlargement at its end and having an upwardly extending tubular housing, a steering wheel shaft located in said upwardly extending tubular housing and having a steering wheel on its upper end.

12. In an industrial truck, the combination of the chassis frame comprising a metal member formed at one end with a bearing member for a steerable wheel, said bearing member having a substantially vertically extending cylindrical bore with a steering wheel support comprising a metal member having a shaft adapted to be received in said bore for rotation of a substantially vertical axis, a driving member carried by the upper end of said shaft, a housing carried by said chassis for enclosing the upper end of said shaft and said driving member, said housing having a radially projecting arm and steering wheel mounted on said arm, operative connections between said steering wheel and said driving member, and a steerable wheel rotatably mounted on said wheel support to be directed by said steering wheel.

13. In an industrial lift truck, the combination of a supporting frame with a steerable ground wheel mounted for rotation upon a vertical axis on said frame, a seat supporting arm mounted for rotation upon a vertical axis on said frame above said steerable ground wheel, said arm carrying an operator's seat and a steering wheel, said steering wheel having means carried by said arm for mechanically connecting the steering wheel with the steerable ground wheel.

14. In an automotive vehicle, the combination of a chassis provided with a steerable ground wheel, said ground wheel being carried by a yoke which is mounted for steering rotation about an upwardly extending axis, a movable supporting member for carrying a seat and a steering wheel, said steering wheel being rotatably mounted upon said movable supporting member in front of said seat, said movable supporting member being mounted for rotation above said steerable ground wheel, whereby the steering wheel and seat and movable supporting member may be moved toward one side to expose that part of the chassis which is normally under the seat for access to the parts of the automotive vehicle.

15. In an automotive vehicle, the combination of a chassis provided with a steerable ground wheel, said ground wheel being carried by a yoke which is mounted for steering rotation about an upwardly extending axis, a movable supporting member for carrying a seat and a steering wheel, said steering wheel being rotatably mounted upon

said movable supporting member in front of said seat, said movable supporting member being mounted for rotation above said steerable ground wheel, whereby the steering wheel and seat and movable supporting member may be moved toward one side to expose that part of the chassis which is normally under the seat for access to the parts of the automotive vehicle, and operative mechanical connections between a shaft supporting said steerable ground wheel and a shaft carried by said steering wheel, whereby the steering wheel may direct the steerable ground wheel.

16. In an industrial lift truck, the combination of a supporting frame with a steerable ground wheel mounted for rotation upon a vertical axis on said frame, a seat supporting arm mounted for rotation upon a vertical axis on said frame above said steerable ground wheel, said arm carrying an operator's seat and a steering wheel, said steering wheel having means carried by said arm for mechanically connecting the steering wheel with the steerable ground wheel, said movable supporting member comprising a cover member provided with an elongated arm, said cover member being mounted above the steerable wheel.

17. In an industrial lift truck, the combination of a supporting frame with a steerable ground wheel mounted for rotation upon a vertical axis on said frame, a seat supporting arm mounted for rotation upon a vertical axis on said frame above said steerable ground wheel, said arm carrying an operator's seat and a steering wheel, said steering wheel having means carried by said arm for mechanically connecting the steering wheel with the steerable ground wheel, said movable supporting member comprising a cover member provided with an elongated arm, said cover member being mounted above the steerable wheel, said steerable wheel being mounted upon a shaft having a driving member located under said cover.

18. In an industrial lift truck, the combination of a supporting frame with a steerable ground wheel mounted for rotation upon a vertical axis on said frame, a seat supporting arm mounted for rotation upon a vertical axis on said frame above said steerable ground wheel, said arm carrying an operator's seat and a steering wheel, said steering wheel having means carried by said arm for mechanically connecting the steering wheel with the steerable ground wheel, said movable supporting member comprising a cover member provided with an elongated arm, said cover member being mounted above the steerable wheel, said steerable wheel being mounted upon a shaft having a driving member located under said cover, said arm forming a housing extending to a shaft carried by said steering wheel, and driving means operating between the steering wheel shaft and the driving member of the steerable wheel and located in the housing of said arm.

19. In an automotive vehicle, the combination of a chassis provided with a steerable ground wheel, said ground wheel being carried by a yoke which is mounted for steering rotation about an upwardly extending axis, a movable supporting member for carrying a seat and a steering wheel,

said steering wheel being rotatably mounted upon said movable supporting member in front of said seat, said movable supporting member being mounted for rotation above said steerable ground wheel, whereby the steering wheel and seat and movable supporting member may be moved toward one side to expose that part of the chassis which is normally under the seat for access to the parts of the automotive vehicle, and means for locking said supporting member against rotative movement on said chassis.

20. In an automotive vehicle, a steering mechanism comprising a steerable ground wheel having an upwardly extending supporting shaft mounted for rotation on a chassis, a driving member carried by the upper end of said shaft and projecting above the chassis, a steering wheel supporting member comprising a cover member and an elongated housing arm projecting laterally from said cover member, said cover member being rotatably mounted on said chassis above said steerable wheel, a steering wheel carried by the end of said arm, and operative mechanical connections between said steering wheel and said driving member.

21. In an automotive vehicle, a steering mechanism comprising a steerable ground wheel having an upwardly extending supporting shaft mounted for rotation on a chassis, a driving member carried by the upper end of said shaft and projecting above the chassis, a steering wheel supporting member comprising a cover member and an elongated housing arm projecting laterally from said cover member, said cover member being rotatably mounted on said chassis above said steerable wheel, a steering wheel carried by the end of said arm, and operative mechanical connections between said steering wheel and said driving member, said connections including a tension member mounted on a driving wheel actuated by said steering wheel, said tension member extending about said driving member above said steerable wheel and being housed in said arm.

22. In an automotive vehicle, a steering mechanism comprising a steerable ground wheel having an upwardly extending supporting shaft mounted for rotation on a chassis, a driving member carried by the upper end of said shaft and projecting above the chassis, a steering wheel supporting member comprising a cover member and an elongated housing arm projecting laterally from said cover member, said cover member being rotatably mounted on said chassis above said steerable wheel, a steering wheel carried by the end of said arm, and operative mechanical connections between said steering wheel and said driving member, said connections including a tension member mounted on a driving wheel actuated by said steering wheel, said tension member extending about said driving member above said steerable wheel and being housed in said arm, said arm being of narrower width than said cover member, and said tension member being engaged by idler wheels at the juncture of said arm with said cover to guide the tension member into the narrower part of said arm.

GEORGE V. JOHNSON.
